Patented Dec. 25, 1973

229,673

LEAD BOX

William E. Danjczek, Easton, Pa., assignor to Koh-I-Noor
Rapidograph, Inc., Bloomsburg, N.J.

Filed July 28, 1971, Ser. No. 167,089

Term of patent 14 years

Int. Cl. D9—03

U.S. Cl. D9—184

FIG. 1

FIG. 2

FIG. 3

FIG. 4

FIG. 5

FIG. 6

FIG. 7

FIG. 1 is a perspective view of a lead box showing my new design;

FIG. 2 is another perspective view showing the lead box in open position;

FIG. 3 is a top plan view on a reduced scale;

FIG. 4 is a side elevational view thereof;

FIG. 5 is a bottom plan view;

FIG. 6 is an end elevational view looking from the left of FIG. 4; and

FIG. 7 is an end elevational view looking from the right of FIG. 4.

I claim:

The ornamental design for a lead box, as shown.
